UNITED STATES PATENT OFFICE.

JOHN V. R. TOWERS, OF WASHINGTON, DISTRICT OF COLUMBIA, ASSIGNOR
OF ONE-HALF TO LEMUEL TOWERS, JR., OF SAME PLACE.

PICTURE-HANGER.

SPECIFICATION forming part of Letters Patent No. 321,866, dated July 7, 1885.

Application filed April 2, 1885. (No model.)

To all whom it may concern:

Be it known that I, JOHN V. R. TOWERS, a citizen of the United States, residing at Washington, in the District of Columbia, have in-

5 invented certain new and useful Improvements in Picture-Hangers; and I do hereby declare the following to be a full, clear, and exact description of the invention, such as will enable others skilled in the art to which it appertains 10 to make and use the same.

My invention relates to certain improvements in picture-hangers, and has for its object to produce a simple, strong, and effective device for attaching a cord to a picture-frame, 15 mirror, or other similar article, in such a manner that the frame can be readily adjusted at any desired height without removing the cord from the supporting hook or nail, and without releasing either end of said cord.

20 It has for a further object to provide a retaining-hook for securing one end of the cord to the frame, so arranged that the cord can be quickly released and the frame removed without lifting the cord off the supporting- 25 nail or raising said frame.

30 The particular construction and arrangement of the various parts of my invention I will now proceed to point out and describe, reference being had to the accompanying drawings, in which—

Figure 1 is a rear view of a picture-frame provided with my invention. Fig. 2 is a side elevation of the windlass or reel on which the cord is wound. Figs. 3, 4, and 5 are details.

35 Referring to said drawings, A is a picture-frame; B, a flat metal plate having its upper end projecting at right angles to the plate, and provided with the guiding-eye b. Said plate is secured to the frame by suitable 40 screws.

C is a spindle passing through the plate B, and secured to the frame.

In the drawings the spindle is shown with a screw-thread and head, and is screwed into 45 the frame. It may, however, be made with a sharp end and be driven into said frame.

D is a hollow windlass mounted on the spindle C, and provided with the outer head or flange, d, and the ratchet-head d' on its inner end. The windlass D and heads d and d' 50 may be all cast in one piece.

E is a weighted pawl, pivoted to the plate B, and, engaging with the ratchet-head, holds the windlass at the point of adjustment.

F is a metal plate, secured to the frame by 55 suitable screws, and is provided with the lower flange, f, and upper flange, f', having the guiding-eye f².

G is a screw-hook having the end g, and, passing through a suitable hole in the plate 60 F, is screwed into the frame.

H is the cord, the ends of which are passed through the guiding-eyes b and f². One end of said cord is secured to the hook G, which is then turned down until the end g engages 65 with the flange f, and thus prevents the cord from slipping off. The other end of the cord is attached to the windlass.

When it is desired to raise the picture without 70 removing the cord from the supporting-hook, it is done by simply turning the windlass, the ratchet-head and pawl holding said windlass and the picture-frame at the point of adjustment.

To lower the frame, release the pawl from 75 the ratchet, and the weight of the picture will cause the cord to unwind.

When it is desired to take the picture down, turn the end g of the hook up to the position shown in dotted lines, and slip the cord off 80 the same.

In Fig. 5 I show a modification of the plate F and hook G. In this modification I provide the plate with two lugs, g', having eyes g². In these eyes I screw a bolt, g³, to which 85 the cord is secured.

Having thus fully described my invention, I claim as new and desire to secure by Letters Patent—

1. In a picture-hanger, the plate B, having 90 the guiding-eye b and spindle C, in combination with the windlass D, mounted on the spindle C, and provided with a pawl and ratchet, substantially as and for the purpose shown and described.

2. In a picture-hanger, the plate F, having 95 the flange f and flange f', provided with the guiding-eye b², in combination with the swivel-hook G, having the end g, substantially as and for the purpose shown and described. 100

In testimony whereof I affix my signature in presence of two witnesses.

JOHN V. R. TOWERS.
